DESIGN FOR A HAT OR SIMILAR ARTICLE

Jesse J. Goodman, Bronx, N. Y.

Application May 6, 1937, Serial No. 69,200

Term of patent 3½ years

To all whom it may concern:

Be it known that Jesse J. Goodman, a citizen of the United States and resident of Bronx, in the county of Bronx and State of New York, has invented a new, original, and ornamental Design for a Hat or Similar Article, of which the following is a specification, reference being had to the accompanying drawing forming part thereof, in which,

Fig. 1 is a plan view of a hat embodying my design; and

Fig. 2 illustrates said hat as worn.

I claim:

The ornamental design for a hat or similar article, substantially as shown.

JESSE J. GOODMAN.
